WELL DEVICE

Herbert C. Otis, Dallas, Tex.

Application July 27, 1938, Serial No. 221,578

22 Claims. (Cl. 166—12)

This invention relates to new and useful improvements in well devices.

One object of the invention is to provide an improved well device for sealing off the annular space between a well casing and a well tubing, whereby the flow of well liquid is directed upwardly through the well tubing.

An important object of the invention is to provide an improved well device including a packer which is normally mounted on the well tubing and is so constructed that the tubing may be disconnected and moved through the packer, after the latter has been anchored within the well casing, whereby the well liquid inlet of said tubing may be readily positioned at the proper elevation or strata in the well bore, and may be moved to various elevations without disturbing the packer.

A particular object of the invention is to provide an improved well device having a flexible packing element which is arranged to be distorted into sealing position by fluid pressures, whereby the weight of the well tubing string need not be utilized to move and hold the element in sealing position; said packing also being retractile from its sealing position by equalization of fluid pressure thereacross, whereby the strain placed on the tubing in pulling the element from its sealing engagement with the casing wall, as is the usual practice, is eliminated.

Another object of the invention is to provide an improved well packer having a fluid-pressure actuated packing element and means for shutting off the fluid pressure from the element, while the device is being lowered through the well casing, whereby accidental or unintentional distortion of the element into sealing position is positively prevented.

A further object of the invention is to provide an improved packer, of the character described, wherein the well tubing is capable of a limited movement with relation to the packer, whereby in the event the well connections become broken and the well pressure is uncontrollable, the packer will act as a stop to limit upward movement of the well tubing and thereby prevent said tubing from being blown from the well by such uncontrollable well pressure.

Still another object of the invention is to provide an improved well packer which is carried by the well tubing and is so connected with the tubing that in the event the packer becomes stuck in the well, the tubing may be disconnected therefrom, after which the packer may be removed by means of a suitable fishing tool, or other means.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, of a well device, constructed in accordance with the invention and showing the same being lowered through a well casing,

Figure 2 is a similar view showing the packing element of the device in its set position,

Figure 3 is an enlarged transverse, vertical, sectional view of the packing element and its associate parts,

Figure 4 is an enlarged horizontal, cross-sectional view taken on the line 4—4 of Figure 1,

Figure 5 is an enlarged horizontal, cross-sectional view taken on the line 5—5 of Figure 1,

Figure 6 is an enlarged horizontal, cross-sectional view taken on the line 6—6 of Figure 1,

Figure 7 is a horizontal, cross-sectional view taken on the line 7—7 of Figure 2, and

Figure 8 is an enlarged isometric view of the suspension collar which connects the tubing with the packing assembly.

In the drawings, the numeral 10 designates an elongate mandrel having an axial bore 11 extending therethrough. The upper portion of the outer surface of the mandrel is substantially cylindrical and a slip supporting sleeve or carrier 12 is slidable longitudinally on this portion. A collar 10' is threaded on the extreme upper end of the mandrel and limits the upward movement of the sleeve on said mandrel. The sleeve 12 is formed with an outwardly directed, annular flange 13 and an external collar 14 is preferably made integral with its lower end. The collar has a plurality of radial slots 15 therein (Figures 1 and 4), which slots are spaced equidistant therearound and the upper ends of gripping elements 16 are inserted within the slots. Each slot is substantially T-shape and the upper end of each gripping element has a cross-arm 16', whereby the elements are suspended from the collar 14. Outward displacement of the upper ends of said elements is prevented by a retaining ring 17 which is inserted within an annular groove 18 provided on the exterior of the collar 14. Since the sleeve 12 is slidable on the mandrel, the gripping elements 16 are movable longitudinally on said mandrel and are also capable of limited lateral or radial movement with relation thereto.

The sleeve 12 is formed with an L-slot 19 which is located between the flange 13 and collar 14 and a radial pin 20 extending outwardly from the exterior of the mandrel 10 engages within this slot and connects the mandrel and sleeve. When the pin is within the lateral or horizontal portion 19a of the slot, the sleeve 12 is in a raised position on the mandrel and said sleeve and mandrel are movable as a unit. By rotating the mandrel to aline the pin 20 with the vertical portion 19b of the slot, said mandrel may be moved upwardly with relation to the sleeve, the pin traveling upwardly in the slot. To hold the sleeve stationary when the mandrel is moved upwardly therethrough, a plurality of friction springs 21 have their upper ends fastened to the collar 14 between the gripping elements 16 and are bowed outwardly to frictionally contact the inner wall of the well casing A.

The outer surface of the lower portion of the mandrel 10 is flared or inclined outwardly to form a slip expanding portion 22. Each gripping element 16 includes an arcuate slip 23 made integral with its lower end and the outer surface of each slip is formed with the usual gripping teeth. The inner surface of each slip contacts the inclined surface 22 of the mandrel and manifestly, as the slip carrier or sleeve 12 moves longitudinally of the mandrel, the slips are moved radially of said mandrel. When the slips are at the lower end of the inclined portion 22, said slips are in an expanded position and the gripping teeth thereof are adapted to engage the inner wall of the well casing A, as will be explained.

The lower portion of the mandrel 10 is enlarged below the slip expanding surface 22, whereby an external, annular shoulder 24 is formed. The lower end of the bore 11 of said mandrel is also enlarged at 11' to provide an internal, annular shoulder 25 and this enlarged portion of the bore is internally screw-threaded to receive the upper end of a supporting sleeve 26. A flexible packing element or sleeve 27 surrounds the supporting sleeve and has its upper reduced end confined within an annular recess 28 which is provided in the extreme lower end of the mandrel. The lower end of the packing element is reduced and disposed within a thimble 29 which has an axial screw-threaded bore 30, whereby said thimble may be attached to the lower end of the supporting sleeve 26. It is noted that the lower end of the bore 30 is reduced to form an internal shoulder 30', against which the lower end of the sleeve 26 may abut and it is preferable that the diameter of this reduced portion of the bore be substantially the same as the diameter of the bore of said sleeve.

When the flexible packing element 27 is in a normal, undistorted position its bore 27' engages the exterior surface of the supporting sleeve 26 and its outer surface is retracted from the wall of the well casing A, as shown in Figures 1 and 3. The sleeve 26 is formed with a plurality of radial ports 31 which are spaced radially and longitudinally thereof, and manifestly, when a pressure is present within the bore of the sleeve 26, such pressure will act through the ports against the packing element 27, whereby said element is distorted or moved to a sealing position with its outer surface engaging the wall of the well casing A (Figure 2). When the pressure within the sleeve 26 is relieved or is less than the pressure exteriorly of the packing element 27, then the inherent resiliency of the material of which the element is constructed returns said

element to a retracted or undistorted position.

The usual well tubing B which extends axially through the well casing A passes through the bore 11 of the mandrel 10 and its outer diameter is substantially the same as the diameter of the bore. The tubing extends downwardly through the supporting sleeve 26 and has its lower end provided with external screw threads, which are preferably left-handed threads. A suspension collar 32 which is arranged to be detachably connected to the lower end of the sleeve 26 of the packer assembly, as will be explained, has the upper end of its bore formed with complementary left-hand screw threads to receive the lower end of the tubing. Since the bore of the mandrel is enlarged at its lower end and also since the sleeve 26 is secured in this enlarged portion 11', it will be obvious that an annular space 33 is provided between the tubing and the sleeve.

For packing off between the well tubing B and the bore 11 of the mandrel, a pair of spaced, annular grooves 34 are formed in the wall of the mandrel bore above the internal shoulder 25. A pressure seal packing ring 35, constructed of flexible packing material, is inserted in each groove and has its inner periphery engaging the exterior of the well tubing. The bottom of each ring is V-shape in cross-section, whereby a pressure from below said rings will tend to distort said rings into tighter sealing engagement with the tubing. The packing rings 35 efficiently pack off around the tubing, while permitting a vertical or sliding movement of the tubing through the mandrel without breaking the seal.

As has been explained, the lower end of the tubing B is screw-threaded into the upper end of the suspension collar 32 which collar is formed with a radially extending lug or projection 36 (Figure 8), which is preferably angular in cross-section. The lug is located near mid-height on the exterior of the collar and is adapted to engage within an inverted L-shaped slot 37 which is provided in the bottom of the supporting sleeve 26, as is clearly shown in Figure 3. The slot has a horizontal or lateral portion 37a and a vertical portion 37b, the latter being open at its bottom and, manifestly, when the lug is within the horizontal portion, the collar 32 is immovable with relation to the thimble 29 and packer assembly. By rotating the collar 32 to aline the lug 36 with the vertical portion 37b of the slot 37, the collar may be moved downwardly from the bore of the sleeve 26 and thimble.

The external diameter of the collar is substantially the same as the diameter of the bores of the sleeve 26 and thimble and when locked in position, with the lug 36 engaging the horizontal portion 37a of the slot, the upper portion of the collar is within the sleeve and thimble, while the lower end of said collar projects therefrom. To pack off between the upper portion of the collar and the bore of the sleeve 26, the collar has an external annular groove 38' which receives a suitable packing ring 38. The outer periphery of said ring engages the bore of the sleeve and prevents pressure from below the packer assembly from entering the annular space 33 between the tubing and sleeve. Thus, when the collar is locked in position within the sleeve 26 and thimble 29, the well pressure from the well casing below the packer cannot enter the sleeve to distort the packing element 27 into sealing position. The lower end of the bore of the suspension collar 32 is screw-threaded and the upper end of a length of pipe or tubing 39

is secured thereto. The lower end of this pipe is perforated, as shown at 40, or the usual well screen (not shown) may be connected thereto. With such arrangement, it is manifest that the well liquid may enter the perforations 40 and flow upwardly through the pipe 39, collar 32 and well tubing B to the surface.

In operation, the packer assembly is mounted on the well tubing B and is connected thereto by means of the suspension collar 32, to which the lower tubing end of the tubing is attached by means of the left-hand threads. The radial lug 36 on said collar is engaged within the horizontal portion 37a of the L-shaped slot 37, in the lower end of the sleeve 26, and as the tubing is run downwardly into the well, the mandrel 10 and packer assembly carried thereby is moved with said tubing. At this time, the gripping slips 23 are in their retracted position with the slip carrier sleeve 12 being held in its uppermost position on the mandrel 10 by the radial pin 20 on the mandrel engaging within the horizontal portion 19a of the slot 19 in said sleeve. Thus, the tubing is utilized to run the device into the well casing A and during the lowering operation, the slips are retracted.

The packing element 27 is also in its normal or undistorted position during such lowering operation since pressure cannot enter the bore of the supporting sleeve 26 because the packing ring 38 on the suspension collar 32 prevents admittance of pressure from below the device. Any pressure within the well casing A will act on the outer surface of the undistorted packing element and such pressure will tend to hold the same in its undistorted position to prevent premature or unintentional distortion of the element into sealing position. There might occur a slight leakage from above the mandrel through the bore 11 and past the sealing rings 35 and such leakage would result in a pressure within the sleeve 26. This slight pressure is desirable during lowering of the device to obviate the danger of the pressure, acting against the exterior of the element 27, forcing and distorting said element through the openings 31. However, it is noted that a relatively high pressure outside the element 27 would be necessary to accomplish this and under ordinary conditions, it would make no difference whether or not a pressure is present within the sleeve 26 during the lowering of the device.

When the assembly has been lowered within the casing to the position at which the packing element 27 is to be set, the tubing B is rotated in a clockwise rotation in Figure 7, which rotates the suspension collar 32 to move the lug 36 on said collar to the end of the horizontal portion 37a of the slot 37 in the sleeve 26 and alines said lug with the vertical portion 37b of the slot. At this time, the mandrel 10 and slip carrier 12 are held against rotation by the friction springs 21 on said carrier. When the lug 36 strikes the end wall of the slot 37, further clockwise rotation of the tubing B will impart a rotation to the mandrel 10 and as said mandrel 10 rotates, the radial pin 20 thereon moves to the end of the horizontal portion 19a and is alined with the vertical portion 19b of the slot 19 in the slip carrier sleeve 12, said sleeve being held against rotation by the friction springs 21. As soon as the pin 20 is alined with the vertical portion of the slot 19, the tubing is raised, whereby the mandrel 10 is moved upwardly with relation to the sleeve 12, the pin moving upwardly in the slot 19. Upward movement of the mandrel with

relation to the sleeve raises the inclined slip expanding surface 22 between the gripping elements 16, whereby the slips 23 are moved radially outward to engage their gripping teeth with the wall of the well casing A. Engagement of the gripping teeth with the casing prevents further upward movement of the mandrel 10 and tubing B and since the well pressure is acting against the bottom of the packer assembly, said assembly is locked in the well casing. It is noted that during the locking operation, the suspension collar 32 is within the lower end of the sleeve 26 and the packing ring 38 prevents admittance of pressure into said sleeve.

After the assembly is locked within the casing A by the slips 23, the tubing B is moved downwardly through the mandrel. Such downward movement is permitted since the lug 36 on the collar 32 has previously been alined with the vertical portion 37b of the slot 37. As the tubing is lowered, the collar 32 moves out of the bore of the sleeve 26 and below the thimble 29, as shown in Figure 2, whereby the well pressure below the mandrel may enter the annular space 33 between the sleeve 26 and tubing B. This pressure cannot pass upwardly through the bore 11 of the mandrel because of the pressure seal packing rings 35 and, therefore, such pressure is confined within the space 33, whereby it acts through the opening 31 against the inner surface of the packing element 27 to distort the same into sealing position. When in sealing position, the outer surface of the element 27 engages the wall of the well casing and, manifestly, the well fluids cannot pass upwardly thereby. Neither can the fluids flow upwardly through the bore of the mandrel, and therefore, said fluids enter the perforations 40 and pass upwardly through the pipe 39 and well tubing B to the surface.

With the packing element in its set position, the tubing B may be moved vertically through the assembly and the packing rings 35 hold the seal during such movement. This makes it possible to position the perforations 40 opposite the desired strata in the well bore after the packer has been set. To permit maximum movement of the tubing, flush joint tubing may be employed. If the usual external couplings are used in the tubing string, then the movement of the tubing is limited to the length of one section as the coupling (not shown) first above the mandrel will strike the cap 10' at the upper end of the mandrel to limit further downward movement. It is noted that when outside couplings are employed, it is desirable that the distance from the assembly in its set position to the bottom of the well bore be greater than the distance from the top of the mandrel to the first coupling thereabove, whereby said coupling will strike the mandrel before the lower end of the pipe 39 strikes the bottom of the hole.

When it is desired to remove the packer, the pressure across the packing element 27 is equalized by creating a pressure above and exteriorly of the element, which is equal to the pressure below and within the element. This may be done by pumping a pressure fluid downwardly into the well casing from the surface or by by-passing the well pressure from below around the packer. This latter method, which is that of by-passing the well fluid pressure around the element will be hereinafter explained.

When a pressure fluid is pumped downwardly into the casing to create a pressure exteriorly of the element, such pressure may be equal to, or

greater than, the pressure within the element. If said pressure is greater, it will tend to force the element inwardly from sealing position, whereby the inherent resiliency of said element need not be depended upon to retract the same. The well tubing B is then raised to lift the suspension collar 32 so that its lug 36 enters within the vertical portion of the slot and moves upwardly therein. Rotation of the tubing in a counter-clockwise direction (Figure 7) moves the lug 36 into the horizontal portion of the slot to again connect the tubing and mandrel. It is noted that as soon as the collar 32 moves into the lower end of the sleeve 26, the packing ring 38 closes the annular space 33 within said sleeve to the well pressure.

After the lug 36 has re-engaged the slot 31, as described, the tubing is lowered to move the mandrel 10 downwardly, whereby the slip expanding portion 22 of said mandrel moves from between the slips 23 to permit them to move inwardly and disengage from the casing A. When the mandrel 10 has moved downwardly a sufficient distance to lower the pin 20 to the bottom of the vertical portion 19b of the slot 19, said mandrel is rotated to engage the pin within the horizontal portion 19a of said slot, whereby the carrier sleeve 12 is again locked to the mandrel to lock the slips in a retracted position. The tubing may then be raised and the entire assembly removed from the well casing A.

If for any reason the teeth of the slips 23 have become so firmly engaged with the casing wall that it is not possible to disengage them by connecting the collar 32 to the sleeve 26 and thereby permitting the weight of the tubing to act downwardly on the mandrel through the pin 36, then the collar 32 may be disengaged and the tubing lowered until the tubing coupling first above the mandrel strikes the collar 10' at the upper end of the mandrel. The weight of the tubing string may then be utilized to jar downwardly on the mandrel to release the slips, after which the collar 32 is re-engaged with the slot 31 and the slips locked in a retracted position, as has been explained, whereby removal of the device may be accomplished.

The lug 36 on the collar 32 may be accidentally sheared or broken off with the result that the connection between the collar and mandrel, as above described, could not be made. To provide an auxiliary means of connection, the collar 32 has a plurality of upstanding projections or lugs 41 which are arranged to engage within complementary slots or recesses 42 (Figure 3) formed in the internal shoulder 25 in the bore of the mandrel 10. If the lug 36 is broken off or sheared, then in removing the assembly from the casing, the tubing B is first lowered so that its coupling (not shown) strikes the mandrel and jars the same downwardly to retract the slips 23. The tubing is then raised until the projections 41 engage within the recesses 42, after which the mandrel 10 may be rotated to engage the pin 20 within the horizontal portion 19a of the slot 19 to lock the slips in a retracted position. The tubing may then be raised to remove the assembly from the casing.

If, for any reason, it is not possible to remove the packing assembly from the casing by means of the tubing B, then said tubing may be disconnected from the collar 32 by rotating the same so as to unscrew the left-hand thread connection between the collar and tubing. During such rotation, the collar 32 may be held against rotation either by the lug 36 engaging the slot 31 or by the

projections 41 engaging the recesses 42. After the tubing is removed, a suitable fishing tool or jar (not shown) may be run into the casing. The tool may be engaged beneath the flange 13 on the carrier sleeve 12 and the mandrel may be jarred downwardly by suitable means. After the slips are released, the fishing tool is raised upwardly which raises the sleeve 12 on the mandrel and engages said sleeve with the collar 10' on the upper end of said mandrel. The assembly may thus be lifted to the surface.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well device including, a tubular packer mounted on a well tubing and movable with relation thereto, means for detachably connecting said tubing and packer, whereby the tubing may be utilized to move said packer in either direction within the well, so as to locate said packer in a desired position therein, means for anchoring the packer in a sealing position within the well, whereby the tubing may be disconnected therefrom and moved therethrough to vary the elevation of the liquid inlet of said tubing in the well bore, and packing elements between the packer and the tubing at each end of the packer.

2. A well device including, a packer having a pressure expansible packing element, means for anchoring the packer in position within the well bore, means to admit fluid pressure to said element to distort the same into sealing position, a well tubing extending axially through said packer and being movable with relation thereto when said packer is anchored to vary the elevation of the liquid inlet of said tubing in the well bore, and means for locking the packer directly to the tubing.

3. A well device including, a packer having a pressure expansible packing element, means for anchoring the packer in position within the well bore, means to admit fluid pressure to said element to distort the same into sealing position, a well tubing extending axially through said packer and being movable with relation thereto when said packer is anchored to vary the elevation of the liquid inlet of said tubing in the well bore, and means for packing off between the tubing and packer to prevent leakage therebetween.

4. A well device including, a packer having a pressure expansible packing element, means for anchoring the packer in position within the well bore, means to admit fluid pressure to said element to distort the same into sealing position, a well tubing extending axially through said packer and being movable with relation thereto when said packer is anchored to vary the elevation of the liquid inlet of said tubing in the well bore, and means carried by the tubing for shutting off the admission of fluid pressure to the element during the lowering of the packer in the well bore and being arranged to be moved when the tubing is moved relative to the packer after the latter is anchored to admit fluid pressure to said packing element for expanding the same.

5. A well device including, a tubular mandrel, a flexible packing element on the mandrel, means

for detachably connecting the mandrel to a well tubing so that such tubing may be utilized to move the mandrel in either direction within a well casing so as to locate said mandrel and packer in a desired position therein, means carried by the mandrel for locking said mandrel in a set position in said well casing, whereby the tubing may be disconnected from the mandrel and moved therethrough to vary the position of the liquid inlet of the tubing in the well, and packing elements between the packer and the tubing at each end of the packer.

6. A well packer including, a mandrel, a distortable packing element carried by said mandrel, means for slidably connecting a well tubing to said mandrel whereby said tubing may be utilized to lower the mandrel through a well casing, means on the mandrel for positively anchoring said mandrel and packing element in the casing, and means to admit a fluid pressure to the packing to distort the same into sealing position.

7. A well device including, a well tubing, a tubular packer mounted on a well tubing and movable with relation thereto, means for detachably connecting said tubing and packer whereby the tubing may be utilized to lower said packer in the well, means for positively anchoring the packer in a sealing position within the well, whereby the tubing may be disconnected therefrom and moved therethrough to vary the elevation of the liquid inlet of said tubing in the well bore, and means for shutting off the admission of fluid pressure to the packer during the lowering operation to prevent premature setting thereof.

8. A well packer including, a tubular mandrel, a distortable packing element surrounding the mandrel and arranged to be distorted by a pressure within the bore of the mandrel, means for lowering the mandrel into a well casing and locking the same therein, and removable means for closing the lower end of the bore of the mandrel during the lowering operation to prevent distortion of the element during such lowering.

9. A well device including, a packer having a pressure expansible packing element, means for anchoring the packer in position within the well bore, and means to admit a fluid pressure to said element to distort the same into sealing position after the same is anchored, a well tubing extending axially through said packer and being movable with relation thereto when said packer is anchored to vary the elevation of the liquid inlet of said tubing in the well bore, said last named means being carried by the tubing and being movable thereby after the mandrel is locked in the casing to open the lower end of the bore of the mandrel to permit the well pressure to distort the packing element.

10. A well device including, an expansible packer having a passage extending therethrough for a well tubing, locking means for engaging the side wall of the well movably carried by the packer and connected therewith so as to be set and released thereby, and means detachably connected with the packer for coupling a well tubing thereto, whereby the tubing may be utilized to move the packer in either direction and to set and release the packer or to be freely moved longitudinally downwardly from its original point of connection with the packer when the packer is locked.

11. In a well device, a packer, means for an-

choring the packer in a stationary packing position in a well, and means arranged to be attached to a well tubing for positively coupling the tubing with the packer, said coupling means being readily detachable whereby the packer may be set and released by longitudinal movement of the well tubing and also whereby the tubing may be freely moved longitudinally downwardly from its original point of connection with the packer when said means is uncoupled, while said packer is anchored.

12. In a well device, a well tubing having a well fluid inlet, a packer, and means for anchoring said packer in a sealing position within a well and against upward and downward displacement by the well fluid, the well tubing extending axially through said packer and normally carrying the same, means for positively connecting the tubing and the packer adapted to be detached, whereby the tubing may be moved longitudinally downwardly from its original point of connection with the packer when said packer is anchored to vary the elevation of the liquid inlet of the tubing in said well bore.

13. A well device including, a fluid-expanded tubular packing having a bore therethrough for the passage of a well tubing, a coupling collar having means for connecting it to a well tubing for movement thereby, means on the collar for detachably engaging it with the packer, and means for packing off between the collar and the packer to shut off the admission of well pressure fluid to the packer when the collar is engaged therewith.

14. A well device including, a mandrel, a packing means carried by the mandrel, means for engaging the side wall of the well movably carried by the mandrel and connected therewith so as to be set and released thereby, a well tubing extending axially through the mandrel and being freely movable therethrough, coacting means on the tubing and mandrel for positively connecting these parts, said means being arranged for detachment whereby the tubing may be utilized to set the well-engaging means and may be disconnected and moved downwardly after such means is set so as to be moved therethrough.

15. A well device including, a well tubing, a packer surrounding said tubing and normally freely slidably relative thereto, means for connecting the tubing and packer, whereby said tubing may be utilized to lower and raise the packer and to position the packer in a well bore, said means being arranged for detachment and means independent of the connecting means for anchoring the packer in a sealing position in the well bore, whereby the tubing may be detached from the packer and moved downwardly with relation thereto when said packer is anchored in its sealed position.

16. A well device including, a well tubing, a packer surrounding the tubing and freely slidably thereon, means for locking the packer in a sealing position in the well bore, a suspension collar carried by the tubing arranged to detachably connect the tubing and packer whereby the tubing may be utilized to position the packer in the well bore, said collar being adapted to be disconnected from the packer after said packer is locked in sealing position, whereby the tubing is free from connection with the packer and is freely movable axially therethrough in either direction relative to the locking means.

17. A well device wherein a tubular packer is

detachably connected with the tubing and the latter is movable longitudinally when the packer is anchored and the packer is movable longitudinally when attached to the tubing and not anchored, in combination with means for anchoring the packer against both upward and downward fluid pressures, and means for sealing between the tubing and the packer.

18. A well device including, a tubular well packer adapted to be mounted on a well tubing, means for anchoring the packer in a sealing position within the well, and a detachable connection between the packer and the tubing for freeing the tubing from the packer so that said tubing may be moved freely downwardly from its points of original connection with the packer when the latter is anchored and also whereby the packer may be moved in either direction when said packer is not anchored and is connected with the tubing.

19. In a well device, a well tubing having a well fluid inlet, a packer for sealing off the well outside of the tubing, means for anchoring said packer against upward and downward displacement in the well and in sealing position, the well tubing extending longitudinally through said packer and normally having a positive connection with the same and arranged to be disconnected from the packer so as to be free from any connection therewith when the same is anchored and movable longitudinally to vary the elevation of the fluid inlet below said packer, and a fluid excluding sealing between the packer and the tubing.

20. A well device including, an elongate packer, an anchoring means movably connected with the packer, means carried by the packer for operating the anchoring means to set and release the same, a well tubing extending longitudinally through the packer, and means positively connecting the packer and tubing together, whereby the tubing may be actuated to set and release

the anchoring means and to actuate and position the packer, said connecting means being arranged for detachment, whereby the well tubing may be freely moved longitudinally downwardly from its original point of connection with the packer when the packer is anchored and said means is detached from said packer.

21. A well device including, a vertically movable tubing, a packer slidably mounted on the tubing, means for anchoring said packer in fixed position in a well bore, a coupling element carried by the tubing, and having means for positively connecting the tubing with the packer for moving said packer upwardly and downwardly through the well bore, said connecting means being readily detachable from the packer, whereby the coupling element may be detached from the packer and the tubing moved downwardly through the packer while said packer is anchored to move said coupling element below the connecting means on the packer whereupon the tubing may be moved in either direction.

22. In a well device, a packer, means for anchoring the packer in a stationary position in a well, a well tubing extending axially through the packer, a coupling element on the packer, means carried by the tubing and disposed to be received within and detachably connected with the coupling element for releasably coupling the tubing to the packer, whereby the packer may be moved with the tubing when the tubing and packer are coupled together, and co-engageable means on said packer and said tubing operable to set said anchoring means when said tubing is moved to disconnect the tubing from the packer whereby the tubing may be moved longitudinally of the packer when said means is uncoupled while the packer is anchored, said coupling element being movable below the connecting means on the packer in either direction.

HERBERT C. OTIS.
